corporation of New York

Application April 9, 1951, Serial No. 14,757
In Cuba November 23, 1950

Term of patent 14 years

(Cl. D1—4)

To all whom it may concern:

Be it known that I, José Luis Prendes Polledo, a citizen of Cuba and a resident of Monzana de Gomez #348 in Habana, Cuba, have invented a new, original, and ornamental Design for an Advertising Attachment for Television Cabinets, of which the following is a specification, reference being had to the accompanying drawing, which forms a part hereof.

In the drawing:

Fig. 1 is a front perspective view of an advertising attachment for television cabinets showing my new design;

The broken lines shown in Fig. 2 are for illustrative purposes only.

I claim:

The ornamental design for an advertising attachment for television cabinets, substantially as shown and described.

JOSE LUIS PRENDES POLLEDO.
